UNITED STATES PATENT OFFICE.

GEORGE F. PIERCE, OF CHICAGO, ILLINOIS.

FURNACE-GRAVE.

1,239,717.

Specification of Letters Patent. Patented Sept. 11, 1917.

Application filed December 11, 1915. Serial No. 66,291.

To all whom it may concern:

Be it known that I, GEORGE F. PIERCE, a citizen of the United States, residing at Chicago, in the county of Cook and State of Illinois, have invented certain new and useful Improvements in Furnace-Grates, of which the following is a specification.

My invention relates to furnace grates, and one object is to provide a sectional grate of novel construction which can be readily assembled for use and wherein any section can be easily replaced at small cost in case it should become damaged.

A further object is to arrange the connecting parts of the sections in such manner that they will not be directly exposed to a fire on the grate, and consequently cannot easily burn out.

A further object is to provide a grate having a conical portion to elevate part of the burning fuel, so that air can penetrate all sides of the flame and thus aid in the consumption of gases and other combustible elements which usually escape unconsumed from the furnace.

Other objects of the invention will hereinafter appear, and in order that said invention may be fully understood, reference will now be made to the accompanying drawings, in which:

Fig. 1 is a horizontal section of a furnace provided with my grate.

Fig. 2 is a vertical central section on line II-II of Fig. 1, with the lower portion of a boiler added.

Fig. 3 is an inverted plan view of the central, circular, conical portion of the grate.

Fig. 4 is a broken detail perspective of parts of the central portion of the grate ready for assembly.

Fig. 5 is a detail perspective of a bell-crank to rotate the central portion of the grate.

Fig. 6 is a section on line VI of Fig. 1. 45 A designates a furnace in which my grate is located, water tubes B being connected by fittings b, preferably, provided to support said grate.

The grate proper consists of a conical, 50 central portion 1, longitudinal grate bars 2, intermediate grate bars 3, and rockable grate bars 4.

The longitudinal grate bars 2 are arranged adjacent the side walls of the furnace 55 and supported by the transverse water-tubes

B. The intermediate grate bars 3, in connection with the two adjacent longitudinal bars 2, surround the conical central portion 1 and have depending marginal flanges 3^a to enter slots in the two adjacent longitudinal bars 2. The rockable grate bars 4 have trunnions 4^a mounted in bearing bars 5, placed upon the transverse water tubes B at the front and rear portions of the furnace; the rockable grate bars 4 at the front portion being connected by a shaker bar 6, while the bars 4 located at the rear portion of the furnace are connected by a shaker bar 7, so that those of each set may be simultaneously operated.

The central, conical portion 1, comprises a center plate 8 and segments 9 surrounding said center plate, to which they are detachably connected, so that the center plate or any of said segments can be readily replaced without throwing away the entire conical portion 1.

The center plate 8 is substantially square in plan view and has quadrangular shaped corners 10, to fit into recesses 10^a in the adjacent corners of the segments 9, which are detachably connected by lugs and bolts 11 and 12, respectively.

Each margin of the center plate 8, between the quadrangular corners 10, has a recess 13 to receive a corresponding projection 14 on each segment 9. Each margin of the center plate 8 also has a downturned lip 15 to interlock with an upturned lip 16, extending inwardly from each segment 9 from a point below the projection 14. When the lips 15 and 16 are interlocked the projections 14 rest on lugs 10^b integral with the quadrangular corners 10. By providing this arrangement of interlocking lips on the center plate 8 and the segments 9, it will be readily understood, that these parts are reliably but detachably connected and by arranging the interlocking lips as shown and described they are protected from direct contact with the fire upon the grate, and hence are not liable to burn out. The segments 9 have radial slots 17 for the downward passage of ashes and the upward passage of air therethrough.

The central, conical portion 1 has depending lugs 18 and is rotatably mounted upon a centrally-disposed shaft 19, journaled in a bearing 20, supported by a plurality of radial arms 21, secured to the undersides of

the intermediate bars 3 and the two longitudinal bars 2 supporting said intermediate bars 3. Loosely mounted upon the shaft 19 is a bell-crank 22, having an upwardly-extending finger 23 which normally stands below the lugs 18.

In order to shake the central, conical portion 1 of the grate, a shaker rod, not shown, adapted to engage one arm of the bell-crank 22 is provided. By turning the shaker rod axially to raise the finger 23 into engagement with one of the lugs 18, the conical portion 1 of the grate can be actuated to clear it of ashes by further proper manipulation of said shaker rod.

From the foregoing description it will be readily understood that I have produced a furnace grate possessing all of the advantages above enumerated, and while I have shown and described the preferred form of my invention, I reserve the right to make such changes in the construction, arrangement and proportion of parts as properly fall within the spirit and scope of the claims.

Copies of this patent may be obtained for five cents each, by addressing the "Commissioner of Patents, Washington, D. C."

Having thus described my invention, what I claim and desire to secure by Letters Patent, is:

1. In a grate of the character described, a center plate having quadrangular corners and locking members, and segments surrounding said center plate having recesses to receive the quadrangular corners and locking members to interlock with the first-mentioned locking members.

2. In a grate of the character described, a rectangular center plate having marginal recesses and locking members, and segments surrounding said center plate provided with projections to enter said recesses and locking members to interlock with those on the center plate.

In testimony whereof I affix my signature, in the presence of two witnesses.

GEORGE F. PIERCE.
